[57] CLAIM

The ornamental design for a weed removing tool, as shown and described.

DESCRIPTION

FIG. 1 is a top plan view of a weed removing tool showing my new design;

FIG. 2 is a front elevational view thereof, the rear being substantially a mirror image thereto;

FIG. 3 is a bottom plan view thereof;

FIG. 4 is an end elevational view thereof taken from the blade end; and

FIG. 5 is an end elevational view thereof taken from the handle end.
